UNITED STATES PATENT OFFICE.

NATHANIEL B. WALES, OF BOSTON, MASSACHUSETTS, ASSIGNOR, BY MESNE ASSIGNMENTS, TO THE WALES COMPANY, OF KALAMAZOO, MICHIGAN, A CORPORATION OF MICHIGAN.

AUTOMATIC HEATING SYSTEM.

1,393,654.

Specification of Letters Patent. Patented Oct. 11, 1921.

Application filed February 17, 1921. Serial No. 445,840.

To all whom it may concern:

Be it known that I, NATHANIEL B. WALES, a citizen of the United States, residing at Boston, in the county of Suffolk and State 5 of Massachusetts, have invented certain new and useful Improvements in Automatic Heating Systems, of which the following is a specification.

My invention relates to automatic house 10 heating systems in which either gas or liquid hydrocarbons are used as a fuel and in which either steam, water or air may be used as the circulative heating fluid. Among the objects attained by my invention are—first 15 complete automaticity with safety; second, a very efficient transfer of the heat from the fuel burned to the radiative surface employed; third, practically instantaneous generation of steam; fourth, the immediate shutting off of the gas or kerosene supply through 20 the failure of any part of the heater to properly function; fifth, the ability to change the fuel employed as, for instance, from gas to kerosene by a simple lever movement. Other 25 objects and advantages will clearly appear from the following description.

In the accompanying drawings—

Figure 1 is a side elevation, partly made in section of apparatus embodying my invention;

Fig. 2 is a horizontal sectional view on the line 2—2 of Fig. 1;

Fig. 3 is a vertical sectional view on the line 3—3 of Fig. 2;

Fig. 4 is a central longitudinal vertical sectional view of the nozzle and bellows control chamber; omitting the liquid fuel nozzle and the central high pressure air jet;

Fig. 5 is an end view of the same looking 40 from the right of Fig. 4;

Fig. 6 is a top plan view of Fig. 4;

Fig. 7 is an enlarged detail view of the thermostatic pilot control device.

This heater is built on designs developed 45 to prevent the external radiation of the very high temperatures attained in the incandescent mass of fire brick and at the same time to enhance the powers of heat absorption of the water containing surfaces to a 50 very high degree within the structure of the heater. This is largely brought about by following the general lines in the heater of a conventional thermos bottle with the interior packed with broken fire brick to develop 55 a maximum deflection of the products

of combustion around and over the water containing surfaces.

Referring to the drawing, 1 is the water containing shell having a central chamber 2 completely closed at its lower end and closely packed with broken silica or fire brick 3, in which fire brick are positioned vertical water tubes 4 connected into the interior of the shell at points 5 and 6, points 5 being below the water level in the water containing section of the shell and points 6 being above the water level in the shell, the water level being shown by the conventional water gage 7. 8 is a blower of any well known construction shown operated by a small electric motor 9, the blower 8 discharging air under blast through nozzle 18, which is secured to the shell at 11. 12 is a pressure control device which stops the motor whenever the pressure in the shell, as shown by the steam gage 13, reaches a predetermined amount. 14 is a metallic bellows such as a "siphon" bellows, or other expansible means subject to the discharge pressure of the blower 8 through the connecting tube 15, which is located in the outer annular passage, the latter being restricted at its inner end by the wedge-shaped sliding member 28, so that a static pressure is created in said annular passage. The bellows 14 is arranged to lift the gas valve 16 off its seat whenever the blower has attained the predetermined discharge pressure. 17 is a given weight adapted to positively seat the gas valve 16 until the correct pressure of the air discharge of the blower has been reached. If the motor should accidentally stop or slow down below that speed which will give the necessary static pressure required for the proper operation of the nozzle 18, the flow of gas from the gas supply pipe 10 will be shut off at the valve 16, preventing in this manner explosions or other accidents.

One of the important features of this invention is the many peculiar advantages arising from the nozzle 18, which properly mixes the gas induced from the gas main with the air blast passing therethrough. The same nozzle structure also highly atomizes the hydrocarbon fuels when liquid fuels are used. Still another feature attained by this nozzle is the secondary admission of air to the gas or kerosene under combustion through the annular orifice 27. This subdivision of the air supply under blast from

the blower materially reduces the roar therefrom which is highly desirable for domestic installations. The broken silica fire brick receives the burning jet of fuel from the nozzle 18 and becomes heated to incandescence and the combustion of the fuel is completed therein.

In the nozzle 18, 19 is the central high pressure air jet which atomizes the liquid fuel supplied to the nozzle 20 by a constant level chamber 21, through the connecting pipe 20'. The annular gas induction chamber 22, which is open to the gas control bellows chamber 23 through part 23^a, has an annular opening 24 through which air from the blower is discharged, and which travels at a high velocity as it passes through the annular intermediate part 24 of the venturi portion, the effect of which is to produce a suction or sub-atmospheric pressure at the mouth of the port 23^a, thereby inducing gas from the chamber 23, into the nozzle 25 through the annular orifice 26. In order to reduce the characteristic roar of the combustion arising from the nozzle mouth 25, I supply the necessary air to support the combustion in two zones, one through the orifice 26 and the balance through the orifice 27 which is made adjustable by the sliding member 28. The sylphon bellows 14 is in communication with the direct pressure air jet from the fan discharge flow duct 30 through the duct 14^a and when the air pressure from the fan has attained a certain predetermined pressure, the bellows distend and lift the gas valve 16 off of its seat 32 by means of the central pin 33, which is threaded and made adjustable by screwing into a threaded boss 16^a depending from the valve 16. A weight 17 keeps the valve 16 tight on its seat 32 and delays the opening of said valve 16 until the air jet velocity is sufficient to insure proper induction and prevent the flame of the combustion from passing backward into the blower.

As previously stated, the air jet from the blower, operating through the medium of the sylphon bellows 14 to lift the main gas supply valve from its seat, forms an automatic safety check against dangerous flooding with gas of the room in which the heater is located.

When the nozzle 18 is operated on kerosene, the fuel is lifted slightly by induction in the supply head above the level maintained in the usual manner by an inlet valve controlled by a float 20' in the carburetor float chamber 21, which is connected to supply pipe 21', and in case the motor stops, the liquid fuel falls below the level of the jet opening 20 thereby preventing flooding of the fuel.

Many dangerous explosions have occurred in automatic gas appliances due to the extinguishing of the gas pilot light, due either

to temporary failure of the supply of gas in the main or to accidental drafts. To safeguard against this occurrence, I have employed a thermostatic metal bar 35, which is so positioned that the flame from the gas pilot 37, or the kerosene fed pilot 38, impinges on said bar both when the pilot light is in a vertical position, which occurs during the period when the blower is at rest, and also when the flame is drawn into the orifice 54 which occurs when the blower is in operation. The thermostatic bar 35 is electrically insulated so that the bar itself acts as a switch member in the relay lines 39 and 40 respectively, which lines are connected in parallel and connect with the gas and kerosene thermostatic switch contacts 41 and 42, by means of the branch conductors 39^a, 39^b and 40^a, 40^b respectively. The relay lines 39 and 40 lead to the controlling magnet 43' of motor relay switch 43 shown diagrammatically in Fig. 1. If, therefore the pilot light should be extinguished for any reason the thermostatic pilot switch 41 or 42 cools and by its contraction opens the corresponding circuit 39 or 40, and in case the room temperature control thermostat 44 should be closed, thus calling for the operation of the system, the motor will stop, due to the opening of the pilot light thermostatic switch, until the pilot light has been properly attended to.

To provide for an automatic check on excessive steam pressures in the generator shell 1 and at the same time to prevent a waste of gas which would occur if the ordinary safety valve were used, in which case a continued burning of gas would ensue during the blowing off of the same, I have devised the pressure control device 12, which is arranged to open up the circuit energizing the magnet of the main relay motor switch 43, by means of the small sylphon bellows 31, which breaks the switch contacts 48. In this manner the entire apparatus is automatically stopped, saving the gas consumption during such times when an excessive pressure occurs.

The thermostat 44 has a single contact 49, which can be varied by adjusting the screw contact 49 by turning the thumb head 51, on which are the indices 50, gaged to represent the temperature range required in house heating. Whenever the temperature of the house is above the predetermined temperature, the contact 49 remains open and the motor relay switch likewise remains in an open position, causing the entire system to stop.

I have indicated at 70 a conventional electric generator as a source of electric energy 125 supplying the motor circuit and also the relay circuit through a transformer 71.

In Fig. 2, 52 is a tube forming a visible opening through the shell 1 into the broken fire brick 3, to thereby permit inspection of 130

the condition of the fire brick. A mica sheet 53 is held in the head of the tube so as to prevent an escape of the products of combustion which normally escape to the chimney through the flue pipe 55.

This automatic heater necessarily embodies a great number of operative parts each part having been found to be essential to the safe and efficient operation of a completely automatic house heating system. The coöordinated safety checks are so operated as to prevent an accident from one or any possible combination of mishaps. To start the system, assuming that the casing 1 has been filled to the proper level from the water supply pipe 45, as shown by indicator 7, the temperature in the house must be below that desired, the pilot light must be in proper operation, the motor must attain its normal speed to safeguard against backfiring and the steam pressure in the generator must be normal, before the motor blower and gas valve will function. One of the features of this system is the external and visible position of the pilots 37 and 38. Whenever the blower is in operation the induction caused by the venturi effect of passage 26 draws in the pilot flame through one or the other port 54 in nozzle 18 and thereby lights the gas or atomized kerosene. The pilots are therefore easily visible and can receive attention. To protect them from drafts, mica chimneys 60 may be placed above the pilots. The kerosene pilot may be formed of a roll of fine wire gauze.

The embodiment of my invention as shown may be naturally varied in its detail and arrangement of parts. Steam, water or air may be used as the heating medium. I have shown the steam supply pipe 65 leading from the top of the casing.

What I claim as new and essential in the operation of a safety automatic heater is embodied in the following claims:—

45 I claim:—

1. In a heating system of the type described, a heating appliance, a fuel-burning

nozzle connected thereto, a motor-actuated blower having a continuously open discharge conduit connected to said nozzle, a source of gaseous fuel connected to said nozzle and a valve therefor, and means operating to open or close the gas supply valve in response to the static pressure in said nozzle, said valve being located exterior to said conduit. 55

2. In a heating system of the type described, a heating appliance, a fuel burning nozzle connected thereto, a gas valve controlling the gas supply to said nozzle, a motor-actuated blower provided with a conduit connected to said nozzle and operating to supply air under pressure to mix with the gas to produce a combustible mixture, a pressure-responsive device in open communication with the discharge conduit from the blower, said device operating to open the gas valve whenever the air pressure discharged from the blower has attained a predetermined static pressure in said conduit, a pilot light to ignite said mixture, a thermostatic pilot switch exposed to the heat of the pilot light, and controlling the operation of said motor-actuated blower and operating to automatically shut off the motor-actuated blower whenever the flame of the pilot light is extinguished. 75

3. In a heating system as set forth in claim 2 and wherein the heating appliance comprises a water heating generator, a master controlling electric circuit controlling the gas supply valve through the medium of the motor-actuated blower, comprising a thermostatic switch located in the compartment heated by the system, a pressure-operated switch subject to the pressure in the generator, said thermostatic pilot switch, said thermostatic compartment switch and said pressure operated switch being connected in series relation in said controlling circuit, whereby said motor-actuated blower is under 90 the control of each of said switches. 85

In testimony whereof I affix my signature.

NATHANIEL B. WALES.
